(57) **CLAIM**

The ornamental design for a package for a binding device, as shown and described.

DESCRIPTION

FIG. 1 is a front view of a package for a binding device showing our new design;

FIG. 2 is a left view thereof;

FIG. 3 is a top view thereof;

FIG. 4 is a bottom view thereof;

FIG. 5 is a perspective view thereof; and,

FIG. 6 is a front perspective view of the package for a binding device showing environment.

In the drawings, the broken lines are for the purpose of illustrating environment only and form no part of the claimed design.
